FLY ESCAPE STRUCTURE

Edward C. Klaiber, Memphis, Tenn., assignor to
 The Wabash Screen Door Company, Minneapolis, Minn., a corporation of Minnesota

Application November 25, 1935, Serial No. 51,414

15 Claims. (Cl. 156—37)

This invention relates to improvements in fly escapes for screened frames, such as doors and windows, and has, among its objects, to provide a simple structure adapted to obtain a maximum efficiency for fly escape, with a minimum liability of entry of rain into the fly escape passages, and which can be manufactured at very small cost.

Features of the invention include: the use of curved-surfaced notches generated on an axis perpendicular to the outer or inner surface of the frame; the use of conical surfaced notches; the use of curved surfaced notches intersecting two adjacent surfaces of one of the frame elements of the door; the formation of these surfaces and notches by a rotating tool, thus making for cheapness; the positioning of the surfaces to be divergent toward the outer face of the rail; the use of curved reflecting surfaces which are arched laterally with respect to the vertical side pieces of the frame, to give a maximum area of reflecting surface; the provision of an upwardly arched surface which makes an angle of substantially thirty degrees or less with the horizontal when the frame is in use; the use of a groove intersecting the notches and curved surfaces of each as means into which a folded part of the screen is thrust; the use of a screen-retaining strip in bridging relation to a notch with its top surface related to the curved surface as a chord; and generally all details of construction, along with the broader ideas of means inherent in the disclosure.

Objects, features and advantages of the invention will be set forth in the description of the drawing forming a part of this application, and in said drawing

Figure 1 is an outer face view of a screen door showing the invention applied;

Figure 2 is an enlarged fragmentary view like Figure 1 but showing only the upper part of the door;

Figure 3 is a detail vertical section through the top rail and escape passage, taken on line 3—3 of Figure 1; and

Figure 4 is a detail vertical section through the top rail and laterally of the passage, taken on line 4—4 of Figure 1.

In the drawing, numeral 1 generally indicates a screened frame, in this instance a door. Numerals 2 designate the side rails and numerals 5, 6 and 7 respectively designate the top middle and bottom rails. The screen is indicated at 9.

The invention has been shown applied to a door and to the top rail thereof, but it is, of course, understood that it may be applied at other levels. In this case, the upper rail is provided

with four conical surfaced notches intersecting the outer and lower sides of the rail, each conical surface 10 forming an arch whose base intersects the bottom surface 11 of the rail 5. Each conical surface is divergent toward the outer face 12 of the frame and the notches form with the screen, fly escape passages leading from the inner surface 13 of the screen over the top of the screen. A single notch may of course be used, but a plurality of such notches are preferable.

Referring to Figures 2, 3 and 4, the inner margin of the rail is recessed as at 14 to receive retaining strip 16, the outer surface of which lies flush with the outer surface 12 of the frame. Extending horizontally inwardly from the bottom 15 17 of the recess 14, is a groove extending the full longitudinal length of the rail and intersecting the conical surfaces of the notches as at 21, see Figure 2. It is noted, of course, that the recess 14 also intersects the conical surface of 20 each recess at two points.

The screening laterally of and between the notches is folded upon itself (see Figure 4) as at 25 and is thrust into the groove as shown. The screen has plain unfolded portions (see Figure 3) 25 indicated at 26, each of which lies against the inner face 27 of the retaining strip 16, which strip forms a backing. The screen and strip 16 and the notch together form the escape passage. The upper edge of the plain flattened portion of the 30 screen, at this point, is substantially flush with the upper edge of the strip 16. The screen retaining strip overlies and is opposed to the groove and bridges the notches to complete the fly escape passages. This strip 16 is related to conical surfaces of each notch as a chord, in such manner that only a relatively small vertical height is given to the escape exits. The area of each opening, as viewed from the front (see Figures 1 and 2) is sufficient for exit, and for entry 40 of light, but not large enough to facilitate entry of rain, nor prominent enough to invite entry of insects. This is important, and is obtainable by the use of the laterally extending curved surface, arching slightly above the upper side of the 45 strip 16.

A feature of this invention is the character of the notches which permits formation by a rotating tool with the axis of rotation of the tool perpendicular to the outer face of the rail, and the use 50 of a conical surface of a particular angle. As shown in Figure 3, the angle which the conical surface makes with the horizontal when the screen is in use is about thirty degrees or less, the horizontal line being indicated at 28 and the 55

angle being generally indicated at 29. This is important as a means for reducing liability of entry of rain.

The bottom 30 of the notch is flat and in this instance is parallel with the outer surface 12 and the inner surface 32 of the rail. In Figure 3, the folded portion of the screen is indicated at a plane beyond the plane of the section, and it will be noted that the screen 9 is continuous across the surface 27 of strip 16, and that it extends to the top of the strip, and it will be further noted that the raw edge of the screen is exposed as at 32 at the top. This is also shown in Figure 2.

The upper margin of that portion of the screen which lies on the surface 27 contacts the surface 27, but although not shown in the drawing, the screen has a tendency to bow slightly outwardly at a point a short distance downwardly from the top of the screen. This is due to the folding of the screen and the thrusting of it into the grooves and these operations also cause the upper edge 32 to be slightly bowed upwardly as shown in Figure 2. It is noted that the raw edge of the screen is exposed at the openings. The slight bowing of the screen away from the surface 27 does not interfere with the reflection of light from the laterally extending arcuate surfaces, but acts to slightly narrow the vertical part of the escape opening, thus lessening the liability of entry of insects from the inside downwardly through this escape opening or passage.

The angular arrangement of the curved surface 10 relative to the horizontal is an important feature. It is again to be noted that the areas of the openings, as viewed from the outside as in Figure 2, for example, are relatively small. At the same time, sufficient light is reflected from a relatively large curved surface downwardly, so that illuminated spots appear along the whole rail and the use of a laterally curved surface substantially proportionately increases the lighting effect, as viewed by a fly at the inside of a screen. These transversely curved or arched surfaces are, as used herein, much more effective as light reflectors than any flat surface, or than any curved surface generated from an axis which is parallel to the long dimension of the rail. The invention is not necessarily entirely limited to the conical shape, although that is the most practical shape and it is also claimed because it has relation to very cheap and efficient manufacture, by means of a rotating tool, and is the most efficient reflecting surface. I am aware that curved surfaces have been used but such curved surfaces have never been generated on an axis which is perpendicular to the front face of the rail, and the arc has not extended laterally, that is in a direction from side rail to side rail of the frame, nor has anyone, insofar as I am aware, used a conical outwardly flared surface, for any of the purposes herein. I am also aware that many attempts have been made to make a practicable, cheap fly escape structure, but of those known to me, the structures are too costly, or too complicated, or interfere with stacking of the frames, or permit entry of rain or insects from the outside, or are inefficient because they do not provide a maximum of reflecting surface with a minimum area of the exit opening, where it intersects the outer surface of the frame.

I claim as my invention:

1. A fly escape structure comprising a screened frame having, in the outer side of one of its rails which is disposed horizontally when in use, an

upwardly outwardly leading fly escape passage having an upwardly laterally arched curved surface the opposite ends of which intersect the bottom of the rail, said surface thereby being disposed so as to be visible to an insect crawling upwardly on the inside of the screen, said surface intersecting the outer surface of the rail, and being angularly disposed so as to be impinged by light from an outside source, and to reflect that light downwardly at the inner side of the 10 screen.

2. A fly escape structure comprising a screened frame having, in the outer side of one of its rails which is disposed horizontally when in use, an upwardly outwardly leading fly escape passage having an upwardly laterally arched curved surface the opposite ends of which intersect the bottom of the rail, thus providing a surface of maximum area, the said surface thereby being disposed so as to be visible to an insect crawling upwardly on the inside of the screen, said surface being divergent outwardly to intersect the outer surface of the rail, and thus being adapted to be impinged by light from an outside source, and to reflect that light downwardly at the inner 25 side of the screen.

3. A fly escape structure comprising a screened frame having, in outer side of one of its rails which is disposed horizontally when in use, an upwardly outwardly leading fly escape passage having an upwardly laterally arched curved surface the opposite ends of which intersect the bottom of the rail, thus providing a surface of maximum area, the said surface thereby being disposed so as to be visible to an insect crawling upwardly on the inside of the screen, said surface intersecting the outer surface of the rail and diverging outwardly and lying at an angle with the horizontal of substantially thirty degrees or less.

4. A fly escape structure comprising, a screened frame having a rotating tool-formed curved-surfaced notch intersecting the outer and lower sides of one of its rails, said surface forming an arch whose base intersects the bottom surface of the rail, the axis of generation of the curved surface being substantially perpendicular to the outer face of the rail, and a screen retaining strip opposed to and spaced outwardly from the bottom of and bridging said notch and having its top surface related to said curved surface as a chord.

5. A fly escape structure comprising, a screened frame having a rotating-tool-formed conical-surfaced notch intersecting the outer and lower sides of one of its rails, the conical surface forming an arch whose base intersects the bottom surface of the rail, and with the conical surface divergent toward the outer face of the rail, the axis of generation of the conical surface being substantially perpendicular to the outer face of the frame, and a screen retaining strip opposed to and spaced outwardly from the bottom of and bridging said notch and having its top surface related to said conical surface as a chord.

6. A fly escape structure comprising a screened frame having a conical-surfaced notch intersecting the outer and lower sides of one of its rails, said surface forming an arch whose base intersects the bottom surface of the rail, the conical surface being divergent toward the outer face of the rail, a screen retaining strip opposed to, spaced outwardly from the bottom of and bridging said notch, and having its top surface related to said conical surface as a chord.

7. A fly escape structure comprising a screened frame having a conical surfaced notch and a screen retaining strip bridging said notch and forming therewith and with the screen a fly escape passage, the conical surface diverging toward and intersecting the outer surface of the frame.

8. A fly escape structure comprising a screened frame having a conical-surfaced notch forming an arch whose base intersects the bottom surface of a rail of the frame and with the conical surface divergent toward and intersecting the outer face of the rail, said notch forming with the screen a fly escape passage, and a screen retaining strip bridging said notch and having its top surface related to said conical surface as a chord.

9. A fly escape structure comprising a screened frame having conical surfaced notches intersecting the outer and lower sides of the top rail, each conical surface forming an arch whose base intersects the bottom surface of the rail and with each conical surface divergent toward the outer face of the rail, said notches forming with the screen fly escape passages, and a screen retaining strip bridging said notches and having its top related to said conical surfaces as chords.

10. A fly escape structure including, a screened frame having, in the outer side of one of its rails which is disposed horizontally when in use, an upwardly outwardly leading fly escape passage having an upwardly laterally arched curved surface the opposite ends of which intersect the bottom of the rail, the said surface thereby being disposed so as to be visible to an insect crawling upwardly on the inside of the screen, said surface intersecting the outer face of the rail, and being angularly disposed so as to be impinged by light from an outside source, and so as to reflect that light downwardly at the inner side of the screen, said structure providing a groove which intersects said curved surface at two points, and into which a folded part of the screen is inserted.

11. A fly escape structure comprising, a screened frame having a curved-surfaced notch in a rail thereof forming an arch whose base intersects the bottom surface of said rail and with the curved surface intersecting the outer face of the rail, and a screen retaining strip bridging said notch and having its top surface intersecting the curved surface of the notch as a chord, the axis of generation of the curved surface being substantially perpendicular to the outer face of the structure, whereby the surface is arched laterally toward the vertical side elements of the frame.

12. A fly escape structure comprising, a screened frame having outwardly flared conical-surfaced fly escape notches in one of the rails thereof, each conical surface intersecting the outer and lower sides of the rail and defining with the screen a fly escape passage leading over the top of the screen, grooves in the outer face of the rail,

intersecting the conical sides of the notches, those portions of the screen lying laterally of and between the openings being folded upon themselves and being thrust into the groove.

13. A fly escape structure comprising, a screened frame having outwardly flared conical-surfaced fly escape notches in one of the rails, each conical surface intersecting the outer and lower sides of the rail and defining with the screen a fly escape passage leading over the top of the screen, grooves in the outer face of the rail intersecting the conical sides of the notches, those portions of the screen lying laterally of and between the openings being folded upon themselves and being thrust into the groove but presenting a plain unfolded portion opposed to each notch throughout its entire area and extending above the groove, and a screen-retaining strip bridging said notches and forming a backing for said plain portion of the screen and having its top surface related to the respective conical surfaces as chords to complete and define exit openings.

14. A fly escape structure comprising, a screened frame having outwardly flared conical-surfaced fly escape notches in one of the rails, each conical surface intersecting the outer and lower sides of the rail and defining with the screen a fly escape passage over the top of the screen, grooves in the outer face of the rail intersecting the conical sides of the notches, those portions of the screen which lie laterally of and between the openings being folded upon themselves and being thrust into the groove but presenting a plain unfolded portion opposed to each notch throughout its entire area and extending above the groove, and a screen-retaining strip bridging said notches and forming a backing for said plain portion of the screen at the opening and having its top surface related to the conical surfaces as chords to complete and define exit openings, the outer surface of the strip being substantially flush with the outer surface of the frame.

15. A fly escape structure comprising, a frame having, in the outer side of one of its rails which is disposed horizontally when in use, an upwardly outwardly leading fly escape passage providing an upwardly laterally arched curved surface, the opposite ends of which intersect the bottom of the rail, the surface thereby being disposed so as to be visible to an insect crawling upwardly on the inside of part of the frame, said surface intersecting the outer surface of the rail and being angularly disposed so as to be impinged by light from an outside source and to reflect the light downwardly at the inner side of the frame, the shape of the passage at its intersection with the outer surface of the frame being that of an upwardly arched segment of a circle intersecting a horizontal chord.

EDWARD C. KLAIBER. 60
